UNITED STATES PATENT OFFICE

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN

TARGET

Application filed January 12, 1931. Serial No. 508,222.

The invention relates to targets more particularly intended for use in connection with air rifles and similar guns. It is an object of the invention to obtain a simple construction which will not be injured by the shot and which will effectually prevent rebound. It is a further object to obtain a collapsible structure which will facilitate shipment. With these and other objects in view the invention consists in the construction as hereinafter set forth.

In the drawing:

Figure 1 is a perspective view of the target holding collapsible frame with the target card and buffer removed;

Figure 2 is a vertical central section through the device in condition for use;

Figure 3 is a similar view of the device with the buffer removed and provided with a sounding bell;

Figure 4 is a cross section showing the device collapsed and ready for shipment.

As shown in Figure 1, my improved target comprises a collapsible frame including a back plate A, folding side plates B B', and a folding bottom plate C. The side plates B and B' have return bent flanges D which form a slot for the reception of a paper or cardboard target E. These side plates are also provided at their upper and lower ends with projecting lugs F adapted to engage apertured ears G which are bent over from the back plate A, thereby forming a hinged connection. The bottom plate C is hinged at one end to the plate B' through the medium of a tongue portion H projecting therefrom and bent to form an eye engaging a slot I in the plate B'. At the opposite end of the bottom C is a tongue J which engages a corresponding slot I' in the side member B. K is a wire brace which at one end has an eye L engaging an aperture in the plate B and at its opposite end has a hook M engaging an aperture in the side B'. The arrangement is such that the bottom C and sides B and B' may be folded and collapsed as indicated in Figure 4 or may be opened out and engaged with each other being held in this position by the brace K as indicated in Figure 1.

Attached to the rear plate A is a curtain N

of canvas or other flexible fabric which is preferably secured by struck-out tongues O overlapping the end of the fabric and then pressed inward to lock it in position. This curtain N when the target is adjusted for use hangs over the brace rod K and in rear of the paper or card which forms the target proper. The lower end of the curtain is weighted by a U-shaped metal strip P clamped thereon.

Where it is desired to use a bell or other sound producing device, a plate Q is provided which is adapted to fit between the side plates B and B' and is provided with tongues for engaging apertures R in said side plates thereby holding it in position. The plate Q has an aperture Q' therein registering with the center or bulls-eye of the printed card E and in rear of this aperture is a bell S secured to the plate by a bracket T.

With the construction as described, the frame may be collapsed as shown in Figure 4 for convenience in shipment. To adjust it for use the side and bottom plates are unfolded and engaged with each other and then locked by the brace rod K. The curtain N is then hung over the rod K and the card E is inserted in the grooves formed by the return bend D. When a shot is fired and penetrates the card E it will strike against the curtain N which by yielding will absorb the kinetic energy without either penetration of the curtain or recoil of the shot. If, however, it is desired to sound a bell when the bulls-eye is struck, the curtain N may be placed back of the brace bar and the plate Q engaged with the frame. This will register the aperture Q' with the bulls-eye of the target and whenever a shot passes through this aperture it will sound the bell S.

What I claim as my invention is:

1. A renewable target comprising a collapsible frame, a target card engageable with said frame when in extended position and a curtain secured to said frame and depending from the upper end thereof in rear of said card.

2. A target comprising a back plate, side plates hinged thereto and provided with grooved guides for receiving a target card,

bracing means for holding said sides in extended position and a curtain secured to said back plate and depending within said frame in rear of said card.

3. A target comprising a back plate, side plates hinged thereto and provided with return bent flanges forming opposed groove guides for receiving a target card, a transverse plate hinged to one of said side plates and detachably engaging the other, a tie brace for holding said side plates in engagement with said transverse plate and a curtain secured to said back plate adapted to hang over said tie-brace in rear of said grooved flanges for the purpose described.
4. A target comprising a collapsible frame including hinged side plates having grooved guides for receiving a target card, a curtain adapted to depend within said frame in rear of said card and a bell plate for use alternatively with said curtain adapted to be clamped by said side plates in rear of said card.

In testimony whereof I affix my signature.

CHARLES F. LEFEVER.
